his Attorney:

UNITED STATES PATENT OFFICE.

RALPH H. UPSON, OF AKRON, OHIO, ASSIGNOR TO THE GOODYEAR TIRE & RUBBER COMPANY, OF AKRON, OHIO, A CORPORATION OF OHIO.

STREAM-LINE SHIELD FOR CABLES, STAY-WIRES, AND THE LIKE.

1,324,014.

Specification of Letters Patent.

Patented Dec. 2, 1919.

Application filed May 29, 1918. Serial No. 237,225.

To all whom it may concern:

Be it known that I, RALPH H. UPSON, a citizen of the United States, residing at Akron, in the county of Summit and State 5 of Ohio, have invented new and useful Improvements in Stream-Line Shields for Cables, Stay-Wires, and the like, of which the following is a specification.

My present invention relates broadly to 10 new and useful improvements in stay wires, cables, or the like, for air craft but has more particular reference to improvements in stream line shields or covers for these wires or cables.

One of the principal objects of my invention 15 is to provide for air craft stay wires a form of shield, which, when properly placed on the wire, will impart to the same a stream line cross section without adding materially 20 to the weight of the stay.

The above and additional objects of a similar nature, which will be hereinafter more 25 specifically treated, may be accomplished by such means as are illustrated in the accompanying drawings, described in the following specification, and then more particularly pointed out in the claims which are appended hereto and form a part of this application.

With reference to the drawing, wherein 30 there has been illustrated a preferred embodiment of the invention as it is reduced to practice, and throughout the several views of which, similar reference numbers designate corresponding parts:

Figure 1 is a perspective view of my stay wire constructed according to the present invention;

Fig. 2 is an enlarged cross section on the 40 line 2—2 of Fig. 1; and

Fig. 3 is a detail perspective view of the stream line shield before it is applied to the stay wire.

Fig. 4 is a cross sectional view of a modification.

The stream line shield of my present invention is of very simple construction and consists only of a rubberized strip of fabric 10 and two bead members 11 and 12.

The fabric 10 is preferably cut on the 50 bias so that the threads will extend diagonally across the stay wires when the shield is put in place thereon as in Fig. 1. The beads are preferably constructed of rubber 55 and are of similar cross sections as will be

noted particularly upon reference to Fig. 2. The cross section of the beads is such that when the bead members are mated (see Fig. 2) they form a substantially wedge shaped rib which extends rearwardly from the wire 60 when the shield is applied thereto, thereby imparting to the wire the desired stream line conformation.

The edges of the fabric 10 are lapped across the inner faces of the beads as at 13. 65 In applying the thread to the said wire, the fabric is passed around the wire and the beads are brought into abutting relation and firmly connected to each other, preferably by cementing.

Should it be desired to use a stream line structure on opposite sides of the wire or strut, a construction similar to that illustrated in Fig. 4 may be used, wherein two pairs of the beads 11 and 12 are positioned 70 on opposite sides of the wire and connected by the fabric strip 10, in a manner as shown.

While I have described my improved shield as being particularly applicable to stay wires for air craft, I desire it to be understood that it may also be applied to cables or any other equivalent stay member, strut or brace in air craft or any other construction where it is desired to impart a stream line cross section to an element not 80 originally possessing such conformation.

What I claim is:

1. As an article of manufacture, a stream line forming structure comprising an elongated fabric element and a plurality of 90 elongated mating members encompassed by the fabric element and connected thereby in spaced-apart relation, each of said members comprising a relatively flat surface adapted to mate with the corresponding flat surface 95 of the other member, and an outer protecting surface, the fabric element comprising a section between the mating members and conformable to the structure which it embraces.

2. As an article of manufacture, a stream line forming structure comprising an elongated fabric element and a plurality of elongated mating members; said fabric element being flexible to lie substantially flat when not in use, and being also conformable to the structure which it is to shield, the members having two relatively flat surfaces, adapted when in use to contact with each other and curved outer protecting surfaces.

100

110

3. A shield for cables, stay wires, struts and the like, including an elongated fabric element which is rubberized and cut on the bias so that its threads will extend diagonally across the structure which it is to embrace, and a pair of bead members relatively similar in cross-section and each having a surface adapted, when the shield is in use, to engage with the corresponding surface of the other member, and an outer protecting surface, the two members, when in engagement, forming a substantially wedge-shaped rib.
4. A shield for cables, stay wires, struts and the like, including an elongated fabric element which is rubberized and cut on the bias so that its threads will extend diagonally across the structure which it is to embrace, and a pair of bead members relatively similar in cross section, and each having a surface adapted, when the shield is in use, to engage with the corresponding surface of the other member, and an outer protecting surface, the two members, when in engagement, forming a substantially wedge-shaped rib, the rib extending away from the article by which the fabric element is embraced and being cemented together to embrace and thus protect said article.
5. A shield for cables, stay wires, struts and the like, including an elongated, rubberized fabric element having its threads extending diagonally, and a pair of bead members encompassed by portions of the rubberized fabric element, said members composed of rubber and being substantially similar in cross-section and having substantially abutting surfaces, the members mating to form a substantially wedge-shaped rib extending away from the article embraced by the fabric element, and cemented to impart a stream line conformation to the shield.
6. An article of manufacture comprising a strip of flexible material and having at its edges separated, flexible, bead-like elements, 45 said bead-like elements adapted to be secured together to form a stream line envelop for cables, stay-wires, struts and the like.
7. An article of manufacture comprising a relatively narrow strip of flexible material and having at its edges flexible bead-like elements spaced apart on said strip, said bead-like elements being substantially wedge shape in form and being adapted to be secured together to form a stream line envelop 50 55 for cables, stay-wires, struts and the like.
8. An article of manufacture comprising a relatively narrow strip of flexible material and having at its edges, and encompassed by said fabric, flexible bead-like elements spaced apart on said strip, said bead-like elements being substantially wedge shape in form and being adapted to be secured together to form a stream line envelop 60 65 for cables, stay-wires, struts and the like.
9. An article of manufacture comprising a strip of flexible material and having at its edges separated rubber bead-like elements, said bead-like elements adapted to be secured together to form a stream line envelop 70 75 for cables, stay-wires, struts and the like.
10. An article of manufacture comprising a strip of rubberized fabric and having at its edges separated flexible bead-like elements, said bead-like elements adapted to be secured together to form a stream line envelop for cables, stay-wires, struts and the like.
- In testimony whereof, I have signed my name in the presence of two subscribing witnesses.
- RALPH H. UPSON.
